ABSTRACT

An item for use on a wet football field whereby the ball is supported on the line of scrimmage in reasonably dry condition since otherwise the ball, even though quickly wiped off, may be again made wet and slippery by recontamination with the wet and muddy turf when placed on the ground at the scrimmage line. This invention envisages a light weight water repellent plate which is easily carried manually and which has cleats on its underside to engage the turf and a replaceable absorptive pad or towel held in place on its upper surface by a peripheral wall on the plate.

SNAP PLATE FOR FOOTBALL

BACKGROUND OF THE INVENTION

The difficulty of holding onto a mud-slicked football especially when being tackled, as well as the increased difficulty in throwing, catching and even in kicking such a ball is well recognized and poses a considerable extra difficulty or hazard to the offensive team which may or may not be completely neutralized during a game. Players and officials may attempt to prevent undue accumulation of mud on a ball in play, sometimes by somewhat casual wiping on the player's uniform and the center may carry a towel for use by himself and by the quarterback at least in drying the hands but the ball may be freshly wetted and/or muddled each time it contacts the ground and in particular, with regard to this invention, every time it is placed on the ground at the scrimmage line.

SUMMARY OF THE INVENTION

As claimed, this invention comprises a combination including a plate, easily carried by hand and impervious to moisture, and provided with cleats on its undersurface to engage the turf and an absorbent pad or towel on its upper surface replaceably held by a peripheral wall formed integral with the plate. Refinement of construction includes making the wall discontinuous, preferably with openings at the corners to facilitate cleaning and drainage, and provision of lip flanges on the interrupted wall for better retention of pad or towel, the openings in the peripheral wall also facilitating finger access to the pad for easy removal of the pad when it is necessary to replace the same.

BRIEF DESCRIPTION OF THE DRAWING

FIG. 1 is a perspective view of the base plate with the pad and football omitted;

FIG. 2 is a bottom plan view of the base plate;

FIG. 3 is an enlarged sectional view taken on line 3-3 of FIG. 2 with the pad in place and

FIG. 4 is a side elevation view of a reduced scale, showing the complete combination of plate, pad and football as in use.

DETAILED DESCRIPTION OF THE PREFERRED EMBODIMENT

Referring now to the drawing, the complete combination is illustrated on a reduced scale in FIG. 4 wherein a football 10 is shown supported on an absorbent pad 12, fragmentarily represented in that figure as held in place by the peripheral upstanding walls 14 on a base plate 16 further equipped with depending cleats 18 which are pressed into engagement with the ground or turf 20, this being easily accomplished since the item is designed for use only when the ground or turf is wet.

The base plate 16 may be a simple planar section of

moisture impervious, light-weight material, ordinarily plastic and this plate may be substantially square as illustrated, oval or otherwise shaped. The plate 16 should be easily carried by hand and of course should not have sharp edges or be otherwise fashioned so as to constitute a hazard to the players should it be inadvertently contacted during scrimmage. To this end the corners 22 are rounded and all edges are radiused.

The upstanding peripheral walls 14 are interrupted with openings 24 provided at the corners at 22 to facilitate cleaning and drainage of any moisture that might otherwise collect within the walls. At the top of the walls inwardly turned lip flanges 26 aid in retention of the replaceable pad 12.

This pad 12 is dimensioned to fit marginally under the lip flanges 26 and is preferably towel-like and absorptive of moisture. The pad is easily replaceable, finger access thereto being facilitated by the openings 24. This last feature has considerable importance due to the conditions of use of the item. If a towel or towel-like pad chosen requires folding prior to insertion the lip flanges are particularly useful in retaining the folded article in flat folded position.

Finally the turf-engaging cleats 18 depend in spaced relation from the underside of the plate 16. These cleats will ordinarily be unitary with the plate 16 and are preferably non-circular in cross section in order to provide maximum anti-slip characteristics, it being recalled that the cleats 22 will ordinarily pass through a limited thickness of grass into rain-softened soil.

I claim:

1. Football equipment, comprising: a generally planar, easily portable base plate of a material impervious to moisture, said base plate having a maximum transverse dimension not substantially greater than the length of an official ellipsoidal football;

upstanding peripheral wall members on said base plate; and a moisture absorbent pad on said base plate of such a size that its edges at least in part abut said peripheral wall members so as to be reasonably retained thereby.

2. Equipment according to claim 1 wherein said pad is a hand towel.

3. Equipment according to claim 1 wherein said peripheral members have lip flanges under which said pad is marginally inserted.

4. Equipment according to claim 1 wherein said peripheral wall members are interrupted to define drainage openings.

5. Equipment according to claim 1 wherein said base plate has turf-engaging cleats on the surface thereon remote from said peripheral wall members.

6. Equipment according to claim 1 and including a football supported on said pad.
